UNITED STATES PATENT OFFICE.

JOHN G. HABBART, OF PRAIRIE DU CHIEN, WISCONSIN.

CIGARETTE CLIP.

Application filed September 13, 1926. Serial No. 135,265.

This invention relates to improvements in cigarette or cigar clips, and has for its object to provide an improved holder for cigarettes and cigars by means of which the 5 smoker will get the full benefit of the smoke and yet be prevented from burning his fingers, or discoloring the same as is the case when holding a cigarette or cigar between the fingers.

10 Another object of the invention is to provide a cigarette holder which will be cheap to manufacture, and which is provided with novel means for manipulating the same.

A further object of the invention is to 15 provide a clip having spring means for clipping the cigarette and including means for readily releasing the said grip on the cigarette when desired.

With the above and such other objects in 20 view as may hereinafter more fully appear, I have invented the device shown in the accompanying illustration in which:

Figure 1 is a longitudinal sectional view of my improved cigarette clip;

25 Figure 2 is a section on line 2—2 thereof;

Figure 3 is an elevational view of a modified form of the invention;

Figure 4 is an elevational view of Figure 1, shown partly broken away.

30 Like reference characters indicate like parts throughout the following specification and in the several views in the drawings in which 1 indicates my improved cigarette holder which comprises a hollow metal casing 2, which may be round, oval, or any other desired shape, one end of said casing terminating in a reduced portion 3, forming a clip member. A similarly formed clip member 4, is pivoted at 5, by means of the pin 6, to the member 2, and has one end 7, hinged to the extracting rod 8, which rod projects longitudinally through the center of the casing 2, and has coiled therearound a spring 9, one end of said spring being 35 fixed to said rod 8, as indicated at 10.

The rod 8, terminates at its free end, in a handle 12, by means of which the clip member 4 is operated, said clip member being held normally in closed position by means 40 of the action of the spring 9, and rod 8. A stopper 13 is provided a suitable distance

below the spring 9, to which one end of the spring 9 is attached.

The casing 2, is provided with a roughened surface 14, near its upper end, in order 45 to prevent the same from turning in the hand of the user. A cap or washer 15, is provided for the upper end 11 of the casing 2, which is adapted to close the same and thus prevent dust and other foreign matter 50 from entering into the casing, and, through the opening 15', forms a guide for the rod 8.

In Figure 3 I show a modification of the invention in which the device is made from a single piece of spring metal, 16, the same 55 being bent into arms 17 and 18, at right angles to one another, the said arms overlapping at 19, and terminating in clips 20, and 21, of a size to readily grip a cigarette or 60 cigar.

In operation the user merely pushes down on the flanges 22, and 23, whereby the clips 20, and 21 are caused to open, thereby permitting the insertion of the cigarette or 65 cigar after which the hold on the same is released and the cigarette or cigar will be 70 held firmly by said clip.

Having described my invention that which I claim to be new and desire to procure by Letters Patent is:

1. A device as described consisting of a tube having an integrally extending jaw, a movable jaw having a lever end pivotally mounted within said tube, and means for operating the last jaw to cooperate with the 85 first jaw to hold a cigarette.

2. A device as described consisting of a tube having an integrally extending jaw, a movable jaw having a lever end pivotally mounted within said tube, and means for 90 operating the last jaw to cooperate with the first jaw to hold a cigarette, said means consisting of a rod slidable within said tube and pivotally connected to said lever end.

3. A device as described in claim 2, a 95 crook in said rod, a disk in said tube and a spring between said crook and disk and coiled around said rod to normally hold the jaws closed upon one another.

In testimony whereof I affix my signature.

JOHN G. HABBART.
